UNITED STATES PATENT OFFICE.

CHARLES AUGUST MOLINE, OF BANCROFT, IOWA.

SLIDING-DOOR FASTENER.

No. 888,342.

Specification of Letters Patent.

Patented May 19, 1908.

Application filed April 1, 1907. Serial No. 365,736.

To all whom it may concern:

Be it known that I, CHARLES A. MOLINE, a citizen of the United States, and a resident of Bancroft, in the county of Kossuth and State 5 of Iowa, have invented an Improved Sliding-Door Fastener, of which the following is a specification.

My invention is an improved fastener for both hinged and sliding doors, and the construction, arrangement and operation of the same are as hereinafter described and illustrated in the accompanying drawings, in which

Figure 1 is a face view of a sliding door, 15 and a portion of a building or fixed structure, with my improved fastener applied as in use. Fig. 2 is a horizontal section on the line 2—2 of Fig. 1. Fig. 3 is a perspective inside view of the fastening. Fig. 4 is a face view of the 20 hinged doors provided with my improved fastener. Fig. 5 is a horizontal section on the line 5—5 of Fig. 1. Fig. 6 is a perspective view of one form of the fastener.

In Figs. 1, 2, A indicates a sliding door 25 supported by hangers and rollers 2 on a fixed overhead bracket 3. In the closed position, as shown it abuts a post or scantling 4 which is attached to the frame or side 5 of the building, or other fixed structure. The form of 30 fastening shown applied in Figs. 1 and 2 and detached in Fig. 6 comprises two elongated plates 6 and 6^a which are connected by a bolt 7. The ends of the latter are in practice screw-threaded and the plates screwed thereon and the ends of the bolt then upset to prevent accidental displacement of the plates. The bolt passes through and is slidable and adapted to rotate in the frame 5 and the post 35 constituting part of it. The fastening is located in such position, or in such proximity to the edge of the doorway that when the longer arms of the plates or portions 6, 6^a are adjusted in the position shown in Figs. 1 and 2 the outer plate 6 will overlap the adjacent 40 edge of the top A and thereby secure the same in the closed position. The inner plate 6^a is provided with a handle 8 consisting of a curved bar whose ends pass through the holes in the ends of the plate. The outer plate 6 45 may be similarly provided with a handle. It is apparent that by this construction the fastener may be operated from the outside or inside. To operate it from the inside the handle 8 is seized and the fastener rotated 50 one quarter around whereby both plates are

brought to a vertical position whereupon the fastener is pulled toward the operator so that the outer plate 6 is drawn back into a recess in the woodwork 5 or at least in such position that it will not interfere with the door A when 60 slid to the left. Such retracted position of the fastener is indicated by dotted lines Fig. 2. In this form of fastener it is thus requisite that the bolt connecting the two plates should be adapted to both slide and rotate in 65 the frame 5, in order to engage it with or disengage it from the door A, as required for fastening or releasing the same.

When the door is closed against the scantling 4 as shown in Fig. 1, a rotatable fastening 10 may be swung over it. In Fig. 4, the fastening is shown applied to hinged bars B, B'. In Fig. 5, the form of the fastening shown is provided with an outer handle 8^a. In Figs. 2, 3, and 5, the numeral 18 indicates 75 a wedge secured to the inner side of the scantling, or door-post, in vertical position, with the point upward, and in such relation to the plate 6^a, that, when the latter is turned down to secure the door, it slides down on the 80 said wedge and thus presses the door tightly against the side or board 5. Besides this function, the wedge serves as a stop for arresting and supporting the fastening proper in the 85 required horizontal position.

I claim:

1. The combination, with the door and door frame, of a fastening comprising parallel plates and a bolt connecting them, the said bolt being arranged to move transversely and rotatably in said frame, adjacent to the edge thereof, and a wedge affixed to the frame between its free edge and the bolt of the fastening, and in vertical position with the point upward, whereby it is adapted 90 for the functions specified.

2. The combination with a sliding door and a door frame having a recess in its outer side adjacent to the rear edge of the door, of a fastening comprising two parallel plates, a 100 bolt rigidly connecting the same, the inner plate having a handle and the bolt being adapted to slide and rotate in the frame whereby the fastening may be operated for engagement with and disengagement from 105 the door, substantially as described.

CHARLES AUGUST MOLINE.
